E. L. STINN

VALVE GRINDER

Filed Feb. 2, 1924

Inventor
E. L. STINN

by *Silas L. Sweet, Atty*

UNITED STATES PATENT OFFICE.

EDWARD L. STINN, OF NEOLA, IOWA.

VALVE GRINDER.

Application filed February 2, 1924. Serial No. 690,177.

To all whom it may concern:

Be it known that I, EDWARD L. STINN, a citizen of the United States of America, and resident of Neola, Pottawattamie County, 5 Iowa, have invented a new and useful Valve Grinder, of which the following is a specification.

The object of this invention is to provide an improved construction for a device for 10 grinding the valves of an internal combustion engine.

A further object of this invention is to provide an improved valve grinding device in which an oscillating lever is employed 15 for communicating oscillating rotary motion to a member adapted for engagement with a valve.

A further object of this invention is to provide a valve-grinding device in which 20 provision is made for periodically permitting raising of the valve from its seat through spring pressure during the grinding operation.

A further object of this invention is to 25 provide a valve grinding device adapted for actuation of valves located in normally inaccessible locations, such as beneath the dashboard of a vehicle on which the engine is mounted.

30 My invention consists in the construction, arrangement and combination of elements hereinafter set forth, pointed out in my claims and illustrated by the accompanying drawing, in which—

35 Figure 1 is a side elevation showing my improved valve grinding device in position for practical use, a portion of the device and also portions of an engine and vehicle being shown in section. Figure 2 is an elevation of one end of the device, a portion of the handle being broken away to economize space. Figure 3 is a cross-section on the line 3—3 of Figure 1. Figure 4 is a detail showing a modified form of rocking 40 bar.

In the construction of the device as shown 45 a frame is formed of spaced side walls 10, 11 which are relatively close together throughout a portion of the length of the frame but flare apart at their forward ends and are rigidly connected at the wider end by a cover or top 12 riveted thereto. The wider ends of the walls 10, 11 also are connected by a horizontal partition 13 spaced somewhat below the top 12, and a pinion 14

is arranged for rotary oscillation in the space between said top and partition, being formed with journals 15, 16 on its upper and lower ends, having bearings in said top and partition respectively. A shaft 17, angular in cross-section, is arranged for rotary oscillation with and vertical sliding movement relative to the pinion 14, and projects above the top 12 and below the partition 13. At its lower end the shaft 17 carries, on a pivot 18, a cross-head 19 having diametrically opposed, downwardly extending lugs 20 adapted for engagement in a common manner in notches formed in the upper face of a valve 21 of the poppet type. 60

A handle 22 is formed on or rigidly fixed to and projects upwardly from the central portion of the frame, said handle being forked at its lower end as shown in Figure 2, the legs of the forks extending into the planes of the two walls 10, 11 of the frame. A lever 23 is arranged in substantially vertical position at the rear or narrower end of the frame. The lever 23 also is forked at its lower end and extends between the walls 10, 11 and is fulcrumed on a pin 24 or rivet extending through said walls. A rack bar 25 is provided and extends through the forks of the handle 22 and lever 23, being 65

pivotedly connected by a pin 26 to said lever near the lower end thereof. The rack bar 25 is offset or bent downwardly between its ends and has its forward portion arranged horizontally and extending through the space between the top 12 and partition 13, being formed with a rack 27 on one face in operative engagement with the pinion 14. A backing block 27' is mounted on the partition 13 in engagement with the rear face of the rack bar, which is adapted for sliding 70

movement against said block and to be held thereby in operative engagement with the pinion. A rocking bar 28 is arranged in substantially horizontal position above the rack bar 25 and extends through the forks of the handle 22 and lever 23, having its forward end overlying the upper end of the squared shaft 17, which shaft preferably is formed conical at its upper end. The rocking bar 28 is formed between its ends with ears 29 by means of which it is pivoted to the handle 22, on a pin or rivet 30. The rear end portion of the rocking bar 28 extends over a pin 31 arranged across the forked portion of the lever 23, and in oscil- 75

lation of said lever said pin slides on the lower face of the rocking bar, holding the rear end thereof in elevated position and causing the forward end thereof to press 5 downwardly upon the upper end of the shaft 17.

In practical use the device is mounted on an engine block such as 32 having a valve seat 33 for the valve 21, and is so positioned 10 that the cross-head 19 overlies the valve and the lugs 20 enter the notches thereof. Then the lever 23 is oscillated manually, causing a reciprocation of the rack bar 25 and a rotary oscillation of the pinion 14 15 and with it the shaft 17 and cross-head 19. The valve is thus caused to grind upon its seat in a common manner, any suitable abrading substance being used in a well known way to cause the valve to seat properly. During the grinding operation the vertically movable shaft 17 is held down by pressure of the rocking bar 28, and this is usually done against the pressure of the valve spring (not shown). It is desirable 20 to permit or cause the valve to be raised from its seat momentarily at intervals during the grinding operation, and for this purpose I have provided one or more kinks or recesses in the lower face of the rocking bar 28, designated at 34. In this instance I have provided two such recesses 34, one at each end of the range of travel of the pin 31, so that when said pin reaches and enters said recesses upward pressure on the 25 rear end of the rocking bar is momentarily relaxed, permitting an upward movement of the shaft 17 through the pinion 14. I have also provided a light spring 35 coiled around the projecting upper end of the shaft 17, engaging at one end the upper end of the pinion and at its upper end a stop such as a flange 36 or pin carried by said shaft, said spring acting positively to raise the shaft and cross-head when pressure is relaxed as just described. Thus 30 pressure on the valve is relaxed at intervals during the grinding operation, and thereupon the valve is raised from its seat by action of its own spring, engagement of the cross-head with the valve being maintained during their simultaneous upward movement so that the grinding operation is continued as soon as the pressure is again resumed, through the rocking bar 28 and pin 31. By having two recesses in the rocking bar the pressure is relaxed and the valve raised at each end of the stroke of the rack bar 25; but if desired one 35 of said recesses, preferably the one near the outer end of the bar, is dispensed with, so that such raising of the valve occurs but once in a complete oscillatory movement, and the grinding operation is more nearly continuous. This formation of the rocking bar 28 is shown in Figure 4. The

walls of the recesses 34 are rounded so that the pin 31 readily moves in and out thereof as the lever is moved.

This valve grinding device is simple and inexpensive of manufacture. It is easily 70 held in place during the grinding operation by light pressure of one hand of the operator on the handle 22, the other hand being employed to operate the lever 23. As the handle and operating lever are removed laterally from the vertical plane of the grinding device, this machine may be employed for the grinding of valves located in otherwise inaccessible places, such as beneath the dashboard 37 of a vehicle on 75 which the engine is mounted, without removing the engine from the vehicle, as clearly shown in Figure 1.

I claim as my invention—

1. A valve grinding tool, comprising a 85 frame, a pinion arranged for rotary oscillation in said frame, a shaft arranged for oscillation with and sliding movement relative to said pinion, a valve-engaging member carried by the inner end of said shaft, a lever fulcrumed in said frame, a rack bar arranged for reciprocation in said frame and having a rack in mesh with said pinion, said rack bar being pivotally connected to said lever, a rocking bar pivotally mounted in said frame and having one end engaging and adapted to exert pressure on the outer edge of said lever, said rocking bar extending across said lever and engaged thereby 90 to hold it in contact with said shaft.

2. A valve grinding tool, comprising a 95 frame, a pinion arranged for rotary oscillation in said frame, a shaft arranged for oscillation with and sliding movement relative to said pinion, a valve-engaging member carried by the inner end of said shaft, a spring pressed means tending to hold said shaft outwardly, a lever fulcrumed in said frame, a rack bar arranged for reciprocation and having a rack in mesh with said 100 pinion, said rack bar being pivotally connected with said lever, a rocking bar pivotally mounted in said frame and having one end engaging and adapted to exert pressure on said shaft against the action of said spring-pressed means, said rocking bar extending across said lever, and a member on said lever engaging said rocking bar and holding it toward said shaft.

3. A valve grinding tool, comprising a 110 frame, a pinion arranged for rotary oscillation in said frame, a shaft arranged for oscillation with and sliding movement relative to said pinion, a valve-engaging member carried by the inner end of said shaft, a spring pressed means for holding said shaft outwardly, a lever fulcrumed in said frame, a rack bar arranged for reciprocation and having a rack in mesh with said pinion, 115 said rack bar being pivotally connected 120 to said lever.

with said lever, a rocking bar pivoted intermediate of its ends in said frame and having one end engaging and adapted to exert pressure on the outer end of said shaft, said rocking bar extending across said lever, and a member on said lever engaging said rocking bar and holding it toward said shaft, said rocking bar being formed with a recess to receive said member at times and permit release of pressure on said shaft at a certain point in the oscillation of said lever.

Signed at Neola, in the county of Pottawattamie and State of Iowa, this 20 day of September, 1923.

EDWARD L. STINN.
